TABLE

John L. Gianfagna, 102 Crestwood Circle,
Marietta, Ohio 45750

Original design application July 17, 1968, Ser. No. 12,808.
Divided and this application May 13, 1969, Ser. No.
19,395

Term of patent 14 years

Int. Cl. D6—01
U.S. Cl. D33—14

FIG. 1

FIG. 2

FIG. 3

FIG. 1 is a perspective view of a table showing my new design;

FIG. 2 is an end elevational view taken from the left in FIG. 1; and

FIG. 3 is an elevational view showing one of the two identical sides.

This application is a division of design application No. D. 12,808, filed July 17, 1968.

I claim:

The ornamental design for a table, substantially as shown.
